ENGINE CYLINDER BLOCK

Fred G. Shoemaker, Ferndale, Mich., assignor, by
mesne assignments, to General Motors Corporation, Detroit, Mich., a corporation of Delaware

Application January 18, 1933; Serial No. 652,303

7 Claims. (Cl. 123—173)

This invention relates to structures which while adequately strong, are of less cubic material content and lighter in weight than equivalent structures now usually made in moulds by casting owing to the limitations of the casting process. It further relates to the manner of dividing or splitting of the structure into separate parts which can be simply produced and then assembled together preferably by press fits upon each other into a built up structure adapted to be soldered, brazed, or welded into a single unit. The invention is also applicable where the complicated nature of the mould makes a casting more expensive than the alternative built up structure.

More particularly, the invention relates to built up steel cylinders, especially for internal combustion engines. In addition to the lighter weight of such cylinders there is an additional advantage in that they permit of a higher power output without thermal distress than is possible with the necessarily much thicker construction of the usual cast iron cylinders. It will be appreciated that thin steel cylinder walls permit the flow of waste heat at a much greater rate to the cooling medium where it is dissipated, than is possible with the thicker cast iron cylinder walls.

The rate of heat development in two-cycle engines particularly may be so high that the poor rate of heat flow through cast iron walls and other parts exposed to heat is a distinct limitation on the power output otherwise obtainable. In such circumstances the use of thin steel for cylinder walls and other parts will enable the attainment of a higher power output.

The aforementioned advantages of built up steel cylinders make them very suitable for the propulsion of aircraft where lightness of weight with maximum power output is of prime importance.

Each cylinder with its individual water jacket will preferably be a complete unit as far as possible, and adapted for combining in a single or multi-cylinder block of any desired number of cylinders with the use of as few additional parts as possible and preferably only top and bottom plates or deck flanges connecting any number of cylinders together to make a single or a multi-cylinder block.

The object of the invention is an engine cylinder block which while of adequate strength will be lighter and thinner than could be produced as a single whole such as the usual "cast" cylinder block, with the added advantage that it will permit of much more rapid extraction or dissipation of the waste heat of the engine cycle

which is not converted into work, or of the work which is converted into heat in any engine to which it may be applied.

It is a further object of the invention to attain the above object by the division of the complete cylinder assembly with all necessary ports, water jackets, and flanges, etc., into component parts which can be simply produced and easily assembled into a built up cylinder block, having regard to the method of joining, as for instance, in the case of brazing, the accessibility of the joints for the placement of the brazing metal or alloy which may be applied in the form of wire or ribbon, powder paste or by spraying.

A still further object of the invention is to form the component parts of the structure as far as possible of stampings which can be cheaply produced of material such as sheet steel, all the parts being assembled together preferably by press fits and supported upon each other in such a way that the units are self holding in their proper position in one complete assembly, ideally adapted for brazing into a single unit in one operation in a furnace with a reducing atmosphere.

The brazing metal or alloy—copper for example—is applied during assembly close to all the joints which are required to be brazed, in any suitable form, i. e., wire, ribbon, powder paste, or it may be sprayed on as a powder mixed with clear lacquer to hold it on the steel. The whole assembly is then heated to the required brazing temperature in a reducing atmosphere. The reducing atmosphere cleans the surface of the steel and the melted copper is drawn into all the joints by capillary attraction, thus welding the whole assembly perfectly.

The drawings show the application of the invention to the two complementary cylinders (having a common combustion chamber) of a U type two-cycle internal combustion engine.

Since for simplicity of construction and embodiment of cylinder units in blocks of any desired multiple of cylinders it is desirable to provide each cylinder with its own water jacket, some means has to be provided for cooling the otherwise uncooled bridge between the two cylinders having a common combustion chamber of a U type engine which forms part of a wall of the combustion chamber and is exposed to perhaps the hottest zone of the burning gases. This has been effected by the use of a water jacket extension piece serving to bridge and connect together the water jackets of each pair of cylinders having a common combustion chamber.

The water jackets do not extend as far upwards as the top deck flange of the cylinders which forms also the bridge to be cooled between each pair of cylinders in order that a single piece—5 which is the water jacket extension piece—may serve at one and the same time to bridge and connect together the water jackets of each pair of cylinders and to form a flared out extension to each of the cylinder water jackets for connection to the periphery of the top deck flange to effect the top closure of the cooling space. It will be appreciated that since the top deck flange forms the aforementioned bridge between the cylinders, it should be as thin as possible, 10 consistent with adequate strength in order that the rate of heat flow to the cooling medium may be as high as possible. The top deck flange is, in fact, made as thin as possible and is made stronger or thicker at other parts other than in 15 the region of the bridges as may be required and hereinafter described.

In such an engine, piston controlled ports for inlet of air or charge mixture are provided in one cylinder and similar exhaust ports are provided 20 in the other cylinder. The cylinder surfaces between the ports, i. e., the port bridges and in the case of the exhaust ports, the material forming the surface areas of the ports themselves is exposed to the heat of the hot combustion gases 25 and must be cooled. In an engine provided with a cooling jacket spaced from the cylinder barrel the ports must be carried or continued through the cooling jacket and the cooling medium must flow through the bridges between the ports.

30 This may be effected by providing the cylinder barrel with an integral sleeve portion partitioning the clearance space between the cylinder barrel and the water jacket in the zone of the ports, the ports being milled as conduits through the 35 sleeve portion and the bridges between the ports being grooved to form with the water jacket, ducts or conduits for the flow of cooling water between the ports.

Alternatively, the sleeve portion might be on 40 the water jacket internal thereof and integral therewith in which case the cylinder barrel would, together with the grooves in the bridges between the ports, form the ducts or conduits for the flow of cooling water between the ports.

45 Alternatively, the sleeve portion may be a unit, i. e., a port piece made separately from the cylinder barrel and the cooling jacket as shown in the accompanying drawings in which it is a ring. As shown, the port conduits are milled through 50 the ring and the bridges between the port conduits are grooved to form with the water jacket, ducts or conduits for the flow of cooling water between the ports.

55 In the drawings: 60 Figure 1 is an elevation of the two complementary cylinders complete with cylinder head.

Figure 2 is an enlarged, partly cut away, part-sectional view of the cylinder provided with inlet ports.

65 Figure 3 is a section on line 3—3 of Figure 2. Figures 4 and 5 are sections on line 5—5 of Figure 6.

Figure 6 is an enlarged part-plan view of the cylinder block with parts broken away.

70 Figure 7 is an enlarged section on line 7—7 of Figure 1.

Figure 8 is a section on line 8—8 of Figure 7.

75 The two cylinder barrels 1 and 2 which may be termed inlet and exhaust cylinders, respec-

tively, consist of seamless steel tubing machined inside and out.

The necessary rectangular port openings 3 in the inlet cylinder barrel and 4 in the exhaust cylinder barrel are next milled in the cylinder walls. A forged hold down flange 5 common to the two cylinders is slipped over the tops of the two barrels and pressed down against a shoulder 6 on each barrel. The two barrels 1 and 2 and the flange 5 are now firmly held together and can be treated as a unit. The port pieces 7 for the inlet cylinder, and 8 for the exhaust cylinder are each ring shaped in the embodiment of the invention illustrated and are machined from a solid ring. The conduits 9 in the inlet port ring 7 10 for the inlet cylinder and which coincide with the ports 3 in the barrel 1 are milled directionally tangential to the median circumference of the cylinder bore as shown in Figure 3 so as to give 15 rotational flow to the incoming charge or air in a clockwise direction as seen in Figure 3. The conduits 10 in the exhaust port ring 8 for the exhaust cylinder and which coincide with the ports 4 in the barrel 2 are milled directionally as shown in Figure 8 to give easy egress of the exhaust 20 gases in the outlet direction. The spaces between the conduits are milled away as shown at 11 and are slotted through the ring at 12 leaving only 25 the thickness of the cylinder barrel itself between the cylinder barrel bore and the cooling medium. 30

These port rings are slipped over their respective cylinder barrels and pressed down until located by a shoulder on the barrel, the respective port and conduit openings in barrels and rings coinciding.

35 It should be noted that the bores of the flange 5 are slightly greater than the outer diameter of the shoulders on which the port rings 7 and 8 rest, so that the flange 5 may be slipped over these shoulders and pressed down against the 40 shoulders 6 on each barrel.

Water jackets 13 and 14 consisting of seamless steel tubing machined inside and out with port 45 openings to coincide with those in the port rings 7 and 8 are now pressed over the port rings and 50 pressed down over a shoulder 15 on the lower hold down flange 5.

Intake and exhaust port chambers 16 and 17 are next assembled. Each chamber is made in two halves divided on the line 18 of Figure 1 with 55 a lap joint. Each chamber may be split in a vertical plane on the port flange side at 19. To provide for the cooling of the exhaust port chamber 17 inner pieces 22 and 23 are placed in the chamber to be subsequently clamped between the 55 chamber and the cylinder water jacket, leaving a water space of about $\frac{1}{16}$ " between inner and outer pieces. The port flanges 20 and 21 are pressed over the pieces forming the chambers. The port chambers are then slipped over the tops 60 of the water jackets of their respective cylinders and pressed down onto a locating shoulder into their proper position. Rows of holes 24 and 25 in the water jacket above and below the ports provide the means for circulating water around 65 the exhaust port chamber.

The upper or top deck cylinder flange 26 has small steel studs 27 plugged on the bottom surface to provide the necessary stock for tapped stud holes in cases where a removable cylinder head is 70 desired. The studs are provided with flats engaging the sides of the channel section flange to prevent them from turning. This upper cylinder flange together with an upper water jacket extension 28 of die pressed sheet steel is next as- 75

sembled by pressing the flange into the jacket extension. The assembly is then pressed into place over the tops of the barrels and water jackets.

This top unit unites the water spaces of both barrels and completes the cylinder block with the exception of the removable cylinder head.

The holes 29 in the upper cylinder flange provide water connections between the cylinder jacket and cylinder head.

10 I claim:

1. In a built up engine cylinder block, in combination a cylinder barrel of steel tubing, a water jacket of steel tubing surrounding and forming a cooling space around the cylinder barrel,

15 a sleeve portion partitioning the cooling space, port conduits through the sleeve portion for the flow of fluid into or out from the cylinder, and grooves in the exterior of the sleeve portion between the port conduits, forming together with the water jacket, cooling spaces and ducts for the flow of water from one side to the other of the partitioned cooling space.

20 2. In a built up engine cylinder block, in combination, the following separately produced units, 25 a cylinder barrel provided with ports for the flow of fluid therethrough, a tubular water jacket spaced from the cylinder barrel and provided with similar ports, a port ring filling that part of the annular space between the cylinder barrel and the water jacket in the zone of the ports having conduits and ducts formed therein, which, together with the cylinder barrel and the water jacket form port conduits for the passage of fluid through the water jacket to the engine cylinder 30 and ducts formed wholly in the port ring for the passage of the water of the jacket between the last named port conduits.

35 3. In a built up U type engine cylinder block in combination two cylinder barrels provided with a common combustion chamber, a top deck flange uniting the two cylinder barrels constituting a bridge between the two cylinders and forming part of the combustion chamber, separate water jackets for each cylinder barrel spaced from the top deck flange to provide water cooling space around the cylinder barrels, and means for connecting the water cooling spaces of the

cylinders and for providing cooling space under the bridge and for completing the closure between the cylinder water jackets and the top deck flange consisting of a water jacket extension piece.

4. In an engine cylinder block according to claim 3, the top deck flange being of minimum thickness in order to provide for rapid heat dissipation and means to provide adequate stock for tapped stud holes in the flange at points where these are required consisting of bossed stud plugs pressed into holes in the flange at points where the tapped stud holes are required and means for preventing the plugs from turning.

5. In a built up engine cylinder block in combination, a cylinder barrel of steel tubing with walls of minimum section throughout its length, a separate hold down flange secured towards one end of the cylinder barrel, a separate top deck flange secured at the other end thereof, ports in the cylinder wall at points intermediate of the flanges, a separate port ring surrounding the ports and secured to the cylinder barrel, a water jacket extending between the aforesaid flanges and provided with similar coincidental ports in its walls, and a port chamber surrounding the water jacket in the zone of the ports.

6. In a built up engine cylinder block, a plurality of cylinder barrels, a top deck flange uniting the cylinder barrels, a tubular water jacket surrounding each cylinder barrel, and means constituting a cooling jacket for the top deck flange and connecting the tubular water jackets to the top deck flange consisting of a water jacket extension piece.

7. In a built up engine cylinder block having complementary cylinders with a common combustion chamber, a plurality of cylinder barrels, a top deck flange uniting the cylinder barrels and forming part of the combustion chamber, separate tubular water jackets for each cylinder barrel and a water jacket extension piece connecting together the water jackets of the cylinder barrels and forming a water jacket for the top deck flange.

FRED G. SHOEMAKER.
